HOT CATHODE ELECTRON DISCHARGE
TUBE

Hubert M. Freeman, deceased, late of East Pittsburgh, Pa., by Max F. Reges, administrator, Bloomfield, N. J., and Wallace G. Wade, Philadelphia, Pa., assignors to Westinghouse Electric and Manufacturing Company, a corporation of Pennsylvania

Original application January 8, 1923, Serial No. 611,263. Divided and this application June 24, 1932, Serial No. 619,600

9 Claims. (Cl. 250—27.5)

The invention relates to hot-cathode electron discharge tubes and it has particular relation to grid-controlled discharge tubes in which the electron-emitting cathode is so heated from a 5 source of alternating, or fluctuating, current as to substantially eliminate the undesirable effects of the varying heating current upon the electron flow in the tube.

Several cathode structures embodying the 10 foregoing features have been disclosed in our co-pending application, Serial No. 611,263, filed January 8, 1923, of which the present application is a division. This application is also a substitute for a divisional application Serial No. 15 120,580, filed July 6, 1926.

Among the objects of the invention is the provision of a cathode element comprising an electron-emitting cathode surface element and an electrically distinct heating element so associated therewith that the fluctuations of the current in the heating element, when energized from an alternating-current source or the like, do not interfere, or otherwise exert a controlling action, upon the flow of electrons from the cathode element to the other space-current electrodes of the tube.

According to the invention, a heater element which may be in the form of a U-shape wire, or the like, with its two legs placed close together, 30 so as to render it substantially non-inductive, is encased in a tubular heat-conducting sheath, the surface of which is adapted to emit electrons when heated. In order to secure prompt electron emission upon turning on the heating current for the cathode, the body of the cathode structure is made relatively small, eliminating excess material that is to be heated. To this end, the cathode sheath is secured directly upon the U-shape heating wires and is insulated therefrom 35 by an oxide coating which is provided either on the surface of the electron-emitting sheath or on the heating wire disposed therein, or on both.

Our invention will be best understood from the accompanying drawing, in which

Fig. 1 is a view, partially in elevation and partially in section, of a thermionic tube, with the associated circuits shown in diagrammatic form, embodying the invention, and

Fig. 2 is an enlarged horizontal sectional view 50 along the line II—II of the cathode of Fig. 1.

Referring to the drawing, which illustrates the invention as applied to a radio-receiving tube of a familiar type, an elongated envelope 1 of glass or the like, has a re-entrant stem 3 terminating in a press 4 into which are welded five

lead-in wires 6 to 10, which serve to support, and to provide connections to, a cathode member 11, a grid 12 and a plate 13 arranged concentrically in the usual way.

The cathode member 11, to which this invention particularly relates, comprises a pair of parallel-disposed wires 15 bent to form a substantially U-shape heater element supported at its two ends by the ends of the two lead-in wires 7 and 8, which serve to supply thereto the heating current. The bent portion connecting the two wires 15 is supported at the top of the tube by means of a carrier rod 17 extending from lead-in wire 6, the latter serving also to make connection to the electron emitting surface of the 15 cathode element, as will be described hereinafter.

The electron-emitting cathode element of the tube is constituted by an oxide coated platinum wrapping 21 surrounding the two heating wires 15. The wrapping is formed by helically winding an oxide-coated strip of platinum, or other suitable material, around the two sections of the heater element 15. The turns of the helix thus constitute an equi-potential sheath or tube entirely surrounding the wires of the heating element. To secure good emission from the surface of the wrapping, the coating thereon is preferably made from oxides of barium, strontium, or other substances having high electron emissivity.

In order to eliminate the undesirable effect of the fluctuations of the heating current in the wires 15, while at the same time maintaining a good electric heat flow connection between the heating wires and the electron-emitting wrapping, suitable insulation is interposed between the heating wires 15 and the adjacent surface portions of the wrapping.

In the form of the invention shown in Figs. 1 and 2, the insulation is provided by the oxide coating 22 on the strip constituting the wrapping 21, thus securing a very good heat exchange between the wires of the heating element and the body which is to be heated to the temperature of electron emission. If additional insulation is 40 necessary, the wires 15 of the heating element itself may be covered by a layer 23 of some insulating material, for instance in the form of an oxide, such as magnesium oxide, which may be made to adhere to the surface of the heating wire 45 in a way similar to the oxides on the platinum strip, of which the wrapping 21 is made.

As stated before, the connection to the electron-emitting surface element of the cathode is made independently of the connection to the heating 50 55

wires 15, for instance, by means of a strip 24 extending from the platinum wrapping 21 to the carrier rod 17.

A tube construction having a cathode, as described above, may be used exactly like the familiar tubes in which the cathode is constituted by a direct-current heated filament. The improved tube has, however, the very material advantages that it may be heated from a source of alternating current, such as a transformer 25, which is connected to the terminals of the heating wires 15, thus eliminating the difficulties incident to the heating-current supply of prior art tubes.

15 The cathode, grid and anode terminal wires 6, 9 and 10 may be connected in the usual way. When operating as an amplifier, for instance, the connections may comprise input leads 26 connected to the grid and cathode element, while the 20 output circuit may comprise a detecting or load device 27 connected in series with a source of plate voltage 28 between the cathode lead-in wire 10 and the cathode lead-in wire 6.

25 The novel features of the invention, which are based on the idea of securing a compact and efficient cathode structure for alternating-current heated tubes by adhesively uniting the insulating spacing member interposed between the outer cathode sheath and the heating wires embodied 30 therein with the surfaces of the sheath or heating wire may be embodied in a variety of other structures which will readily suggest themselves to those skilled in the art.

We claim as our invention:

35 1. A thermionic cathode electron-discharge tube comprising a cathode structure comprising a U-shape heating wire having closely disposed parallel heater sections and a tubular sheath comprising platinum strip wound about said heater sections, the outer surface of said sheath being adapted to emit electrons when heated, and a surface layer of insulating oxide intervening between said heater sections and said sheath.

40 2. A thermionic cathode electron-discharge tube comprising a cathode member comprising a U-shape heating wire having closely disposed parallel heater sections and a tubular sheath of conducting platinum ribbon wound upon said heater sections, the outer surface of said sheath being adapted to emit electrons when heated, the outer surface of said heater sections having a 45 coat of magnesium oxide.

45 3. A thermionic cathode electron-discharge tube comprising a cathode structure comprising a U-shape heating wire having closely disposed parallel heater sections and a tubular sheath of conducting material embracing said heater sections, the outer surface of said sheath being adapted to emit electrons when heated, said

sheath comprising a helically wound strip of conducting material having an oxide coated surface engaging the surface of said heater sections.

5 4. An electron-discharge tube, comprising a cathode structure comprising an electrically conducting heating element, an electrically conducting strip having an electron-emitting surface of strontium oxide wound about said heating element and electrically insulated therefrom by means of magnesium oxide.

10 5. An equipotential cathode structure comprising an equipotential surface, a substantially non-inductive electrical heater for rendering said surface thermionically active, said non-inductive heater having an insulating layer adhering to its 15 outer surface.

6. An equipotential cathode structure comprising an equipotential surface, a two leg heating wire having closely disposed heater sections within said equipotential surface and an insulating 20 heat-resisting coating formed on said heater sections and adhesively bound thereto.

25 7. An electron discharge device comprising a plurality of cooperating electrodes, at least one of said electrodes being an indirectly heated 30 electron-emitting cathode comprising a metallic sleeve serving as an electron-emitter and a heater surrounded substantially by said sleeve, but maintained out of direct electrical contact therewith, said heater comprising a two-leg electric conductor anchored about its center and connected at its ends to lead-in conductors and comprising an insulating, high heat-resisting coating formed on at least said legs and at least physically adhesively bound thereto.

35 8. A cathode capable of being heated by alternating current for electron-emitting purposes comprising an inner refractory metal wire, a metal sheath therearound insulated from the inner wire by refractory oxide and coated with 40 electron-emitting oxides, the component parts of said cathode being disposed in non-inductive relation.

45 9. In an electron discharge device, an indirectly heated cathode comprising a metallic cathode sleeve serving as an electron-emitter, a filamentary heating element having a plurality of legs for heating said cathode sleeve and adjacent thereto, and an insulating, refractory coating, containing an insulating compound of an element having a low atomic number, on said heating element and being normally substantially non-conductive and solid at the operating temperatures of said heating element and adhesively bound to at least a part of said heating element.
